PORTABLE SIGN

Frederick W. Stein and Earl E. Hellener, Atchison, Kans.

Application February 5, 1953, Serial No. 335,218

10 Claims. (Cl. 40—125)

The present invention relates in general to signboards, and it deals more particularly with small portable signs designed for intermittent use, such, for example, as the safety markers that are displayed at street crossings adjoining a school at the hours when children are going to and from the school, or temporary highway warnings of the type employed by road construction and maintenance crews to appraise motorists that a section of the road is under repair.

An object of the invention, broadly speaking, is to provide a sign of the character indicated which is simple and economical to manufacture but sturdy and durable so as to be longlived in use; which provides an effective, eye-catching and attractive display when in use; and which can be handled easily and efficiently from the standpoint of installing it or removing it from location.

More specifically, an object of our invention is to provide a relatively lightweight sign which is foldable or collapsible for compact storage when not in use and which folds automatically upon being removed from location whereby it can be handled speedily, and large numbers of such signs can be collected or otherwise removed from use in a very short time. Coupled with these advantages, however, it is an object to provide a sign which will not fold or collapse under the influence of wind pressure or accidental impact when it is on location and which, on the contrary, is firmly self-supporting in an upright position and has its own means for anchoring it securely against shifting and toppling.

Other and further objects of our invention, together with the features of novelty whereby the objects are achieved will appear in the course of the following description of the invention.

In the accompanying drawings which form a part of the specification and are to be read in conjunction therewith and in which like reference numerals are employed to indicate like parts of various views:

Fig. 1 is a front elevational view of a collapsible signboard embodying our invention showing same in the self-supporting upright position it occupies when in use, parts having been broken away for purposes of illustration;

Fig. 2 is a side elevational view of the same;

Fig. 3 is a view corresponding to Fig. 2 but showing our signboard collapsed for storage and convenient handling;

Fig. 4 is a sectional elevation taken along the line 4—4 of Fig. 2 in the direction of the arrows; and

Fig. 5 is a fragmentary cross section taken along the line 5—5 of Fig. 2 in the direction of the arrows.

Referring more particularly to Figs. 1 and 2, our signboard has a base 10 carrying an upright post 12. The opposite faces of the base may bear any desired legend 14, such as "School Crossing," or "Men Working"; and a brightly colored flag or pennant 16 (or, if desired, an auxiliary sign placard) can be affixed to the upper portion of the post.

The base 10 comprises a pair of generally rectangular

2

panels 18 and 20 made of sheet metal or like material of suitable rigidity. Along their upper edges the panels are bent toward one another as shown at 22 and then upwardly to form on each panel a marginal lip portion 24 offset slightly from the plane of the panel proper.

The two panels are hinged together at their upper edges, conveniently by means of rings 26 each of which is received in matching holes 28 in the aforementioned marginal lips. This arrangement provides a very economical and perfectly satisfactory form of hinge, but it will be understood that any alternative form of known hinge may be substituted therefor, it only being necessary that the lower edges of the panel be capable of swinging toward and away from one another.

As previously suggested, the outer faces of the sign panels may bear any desired legend 14; and the inner faces have a pair of brackets 30 and 32 welded or otherwise affixed thereto. A foldable toggle composed of links 34 and 36 has its ends hingedly connected to the opposite brackets at 38 and 40, respectively.

Extending upwardly from the midpoint of the toggle is a hollow post or sleeve 42, the upper portion of this member being loosely received in an opening 44 (see Fig. 4) formed by cutting out small confronting notches in the bent-over portions 22 and contiguous lip portions 24 of the two panels. The sleeve has at its lower end a depending offset lug 42a which is connected to the toggle joint by means of the pivot bolt or rivet 46. Above the upper edges of the panels, sleeve 42 has an integral radial flange 42b, this being somewhat larger in diameter than the size of opening 44.

As may best be seen in Fig. 2, the position of the flange 42b on the sleeve is such that when the flange rests on the upper edges of the panels it supports the center pivot 46 in a position slightly below the level of the end pivots 38 and 40 whereby the midpoint of the toggle is just below dead center and the lower edges of the panels thus are separated substantially as far as the toggle will permit. Because the toggle cannot fold downwardly from the position illustrated in Fig. 2, the lower edges of the panels cannot move together except upon an upward movement of the toggle, which necessarily involves a slight initial outward displacement of the panels as the toggle passes through dead center. This arrangement is effective to prevent accidental folding of the sign under the influence of inwardly directed force imposed on the opposite panels due to wind pressure or the like.

Post 12 is received in the sleeve 42 and has an integral bead 12a welded or otherwise secured thereto at a point below the lower end of the sleeve. The lower end of the post is pointed as shown, and the upper end is provided with a hand grip or lifting ring 12b.

As will be clear from Figs. 1 and 2, when our sign is in use, the lower edges of the panels 18 and 20 are widely spread to form a firm supporting base for the whole assembly. The base cannot fold even under the influence of relatively strong wind pressure, being held open as pointed out hereinbefore by the toggle links 34 and 36 which in turn are held against folding upwardly due to the downward over-center disposition of pivot 46, as well as by the weight of sleeve 42 itself. The lower end of post 12 rests on the ground to provide another point of frictional resistance to shifting of the base, or, if the sign is located off the pavement, the post may be forced downwardly into the ground as shown by dotted lines in Fig. 2 to provide positive anchorage.

Thus standing, the legends on the base panels are conspicuously displayed, and as previously suggested may be augmented by an eye-catching pennant 16 or the like carried on the upstanding post.

Signs of the kind shown are particularly well suited

for intermittent use, inasmuch as they may easily be removed from location and stored or transferred to other locations. Assuming that a given set of such signs have served their purpose, they can quickly be picked up and collected by men working in a truck or like conveyance. It is only necessary to drive the truck along side each standing sign and, without leaving the truck, reach out and lift the sign abroad by means of the loop 12b at the top of the post. When this is done, the upward force (see Fig. 3) causes the enlarged bead 12a to engage the base of sleeve 42, shifting the latter upwardly and causing it to fold the toggle upwardly whereby the base panels 18 and 20 automatically swing together as shown in Fig. 3.

Thus, in a single swift operation, the sign is both removed from standing position and folded so that it may be laid flat in the truck bed or stacked upon other signs similarly folded. It will be obvious that a large number of signs occupy only a small space when so folded, making for compact storage and easy handling. At the same time the signs remain ready to be restored to instant use by the simple act of swinging the lower edges of panels 18 and 20 apart as shown in Fig. 2. Ring 12b can be used for hanging the sign, if such is desired.

From the foregoing it will be seen that this invention is one well adapted to attain all of the ends and objects hereinbefore set forth, together with other advantages which are obvious and which are inherent to the apparatus.

It will be understood that certain features and subcombinations are of utility and may be employed without reference to other features and subcombinations. This is contemplated by and is within the scope of the appended claims.

Inasmuch as various possible embodiments of the invention may be made without departing from the scope thereof, it is to be understood that all matter herein set forth or shown in the accompanying drawings is to be interpreted as illustrative and not in a limiting sense.

Having thus described our invention, we claim:

1. In a portable sign, a pair of panels hinged together at their upper edges whereby their lower edges can swing toward and away from one another, a foldable toggle between the two panels with its ends hinged to the respective panels to limit the distance the lower edges thereof can move apart, an upright sleeve connected at its lower end to the toggle and extending upwardly therefrom through an opening in the hinge between the panels whereby it projects above the upper edges of said panels, said sleeve movable axially through said opening and effective upon upward movement to fold said toggle upwardly thereby to draw the lower edges of the panels toward one another, a post slidably received in said sleeve and projecting beyond the opposite ends thereof, said post having below the sleeve a shoulder adapted to engage the lower end of the sleeve and apply an upward thrust thereon upon lifting of the post.

2. A sign as in claim 1 wherein said post has a hand grip at its upper end for lifting same.

3. A sign as in claim 1 wherein said post has a loop at its upper end for hanging the sign.

4. A sign as in claim 1 having a display device affixed to the projecting upper portion of the post.

5. A sign as in claim 1 wherein said post has a pointed lower end adapted upon downward movement of the post relative to the sleeve to enter the ground to anchor the sign.

6. A sign as in claim 1 wherein said sleeve has an outwardly projecting flange positioned to rest on the upper edges of said panels when said toggle is substantially fully extended.

7. In a portable sign, a pair of opposed, generally upright panels, each having along its upper edge a flange projecting toward the other panel, means hingedly connecting said flanges together whereby the lower edges of the panels can swing toward and away from one another, said flanges and hinge means being constructed and arranged to space said panels apart by a predetermined distance when the panels are parallel to one another, said flanges having opposed notches substantially midway between the lateral edges of the panels to provide a central opening through said hinge, a foldable toggle between the two panels with its ends hinged to the respective panels to limit the distance the lower edges thereof can move apart, said toggle comprising a pair of links pivoted to one another at a point below and substantially in vertical alignment with said opening, an upright sleeve connected at its lower end to said pivot and extending upwardly therefrom with its upper portion loosely received in said opening, said sleeve having an outwardly projecting flange positioned to rest on the upper edges of said panels when

30 said toggle is substantially fully extended, said sleeve movable axially through said opening and effective upon upward movement to fold said toggle thereby to draw the lower edges of the panels toward one another, a post slidably received in said sleeve and projecting beyond the opposite ends thereof, said post having below the sleeve a shoulder adapted to engage the lower end of the sleeve and apply an upward thrust thereon upon lifting of the post.

45 8. A sign as in claim 7 wherein said post has a hand grip at its upper end for lifting same.

9. A sign as in claim 7 wherein said post has a loop at its upper end for hanging the sign.

10. A sign as in claim 7 wherein said post has a pointed lower end adapted upon downward movement of the post relative to the sleeve to enter the ground and anchor the sign.
